UNITED STATES PATENT OFFICE

DUDLEY WILLCOX, OF LAWRENCEVILLE, NEW JERSEY, ASSIGNOR TO AJAX ELECTRO-THERMIC CORPORATION, OF AJAX PARK, NEW JERSEY, A CORPORATION OF NEW JERSEY

ELECTRIC INDUCTION FURNACE

Application filed August 13, 1928, Serial No. 299,158, and in Great Britain September 8, 1927.

My invention relates to the cooling of windings for electric induction furnaces.

One purpose of my invention is to utilize the conductivity of copper to carry the heat away from a section so that water-cooling can be effected by water located in a protected position.

A further purpose is to form the current-carrying part of an inductor of solid material close to the furnace and to locate the water cooling section upon the outside where the water will be protected against contact with molten metal leaking from the furnace by the body of the coil.

15 A further purpose is to attach cooling elements to a furnace coil at intervals only about the circumference, relying upon these elements to cool by heat conductivity those portions of the coil lying between.

20 Further purposes will appear in the specification and in the claims.

I have preferred to illustrate my invention by a few forms only among the many in which it may appear, selecting forms which are practical, efficient and reliable and which at the same time well illustrate the principles of my invention.

Figure 1 is a top plan view showing one embodiment of my invention.

25 Figure 2 is a section of Figure 1 taken upon line 2—2.

Figure 3 is a view corresponding to Figure 1 showing the invention applied at intervals about the furnace coil.

30 Figure 4 is a side elevation of the structure seen in Figure 3.

Figure 5 is a section of Figure 3 taken upon line 5—5.

35 Figure 6 is a top plan view of a furnace in which coil supports interfere with the placing of the cooling elements.

Figure 7 is a side elevation of the structure seen in Figure 6.

40 Figure 8 is a section upon line 8—8 of Figure 6.

Figure 9 is a top plan view of a further form.

45 Figure 9a is a fragmentary top plan view showing a slight modification of Figure 9.

Figure 10 is a side elevation of the form seen in Figure 9.

Figure 11 is a section of Figure 9 taken upon line 11—11.

50 Figure 12 is a fragmentary section similar to Figure 11, but showing a modification. In the drawings similar numerals indicate like parts.

55 My invention is intended to safeguard application of water cooling to the coils of electric furnaces and, though applicable most conveniently and to the greatest benefit to inductor coils for furnaces of the so-called coreless type (lacking interthreading of the coils by transformer or crucible iron) is suited also for use with windings of so-called core type furnaces.

60 By illustrating the coreless type only it is not intended to suggest that the invention is useful in this type alone.

65 Existing windings of furnace inductor coils are made of tubing or of solid strips or straps of copper. The tubing is cooled by water passing through the tubing. One sample of water cooled coils is to be seen in Northrup Patent, No. 1,328,336.

70 When the inductor is made of solid metal it is necessary to cool the coil by a blast of air or other means to take the place of the water cooling in the hollow tubular form.

75 My invention contemplates cooling an otherwise solid coil by water cooled means located outside of the coil where the water-carrying members are protected against flow of molten metal leaking from the furnace. These water cooling members may be attached to the coils, but ordinarily used to be attached at intervals only along the length of the coils.

80 Instead of direct connection to the coils it is ordinarily sufficient to attach the members to the coils at intervals along the coil lengths by heat-conducting tabs.

85 The points of attachment may be located at different points along the lengths of the coils or at different points about the circumference or both. In the case of larger coils it is desirable to put several tabs on each turn.

90 Though the invention is valuable for small furnaces its paramount value as a safeguard

against injury from water contact with molten metal makes it still more useful with large furnaces.

With its greater power of cooling as compared with air cooling and spacing the water cooling outside of the furnace coils my invention makes it possible to wind the turns of the primary coils axially closer together than is possible with the air cooled coils. 10 using very thin electrical insulators between in the form of cut rings or strips of mica, for example, which will completely fill the space between the turns instead of the small insulating pieces at intervals about the coil now required with air cooled coils in order to give greater room for penetration of cooling air between the turns.

This makes it possible to carry more turns 20 per axial inch of coil length than previously and to obtain a greater number of ampere turns about a given mass or charge of material to be heated than could otherwise be secured.

The additional safety of the present invention as compared with the usual form of water cooled coil made of conducting tubing through which a stream of water is passed will be clear from the fact that molten metal leaking through the insulation of a furnace 30 using a tubular current-carrying inductor coil may melt the inside of one or more of the conducting turns of the coil. This would not only allow the molten metal to engage the water, but this would take place at a point on the inside of the coil where the resulting steam or vapor cannot escape, with the possibility of an explosion which would blow molten metal out of the furnace. An interior line of discharge of the water from 40 the coil also throws the water toward the charge increasing the danger. The present invention keeps the cooling liquid well away from the molten metal, discharges the cooling liquid outwardly and utilizes the coil as 45 a shield and guard against flow of molten metal and water toward each other.

In Figures 1 and 2 the inductor 15 is wound from a copper strip of rectangular cross section. Every few turns the strip inductor is 50 connected by sheet copper tabs 16 with copper tubing 17 brazed to the tabs. The tubes are connected together by sections 18 of rubber hose. Inlet and outlet for water supply and discharge are shown at 19 and 20. The surplus heat from the coil is conducted to the cooling tubes through the tabs and is carried away through the water.

In Figures 3, 4 and 5 the tabs and water-cooled tubes connected with the inductor 60 every few turns in Figures 1 and 2 and there located in the same circumferential parts of the turns are replaced by copper blocks or strips 16' secured progressively about the circumference of the coil upon successive turns 65 of the coil. These are bored at 21 to pass the

water directly through the blocks and the passages are connected in series by rubber tubing 18' and nipples 22. These passages with their walls in the blocks are viewed as in effect tubes but the larger masses of these block tabs, their larger number and more general distribution and the better contact of the water with the tabs from the standpoint of heat conduction makes this form a very much better cooling system than that in Figures 1 70 and 2.

In each of these forms shown in Figures 1-5 each turn of the inductor forms a single strip of copper.

In Figures 6 to 12, however, each inductor turn comprises a plurality of strips 15' electrically in parallel, greatly increasing the conductivity of the turn. In all of these figures heat insulation within the coil is shown at 23, electrical insulation between the coil and the heat insulation is shown at 24 and insulation between the conductors of each turn to reduce eddy currents and between the turns is seen at 25. In Figures 6, 7 and 8 non-metallic coil supports are shown at 26. 90

Figures 9, 10 and 11 correspond in all of these parts with Figures 6, 7 and 8 except for the fact that laminated magnetic return circuits for the magnetic flux of the coil are shown at 27 instead of the coil supports 95.

The water cooling of Figure 6 is secured by flattened copper tubing 28 flat-wound about the turns and brazed or soldered to the turns between the supports or at any other suitable interval as at 29 and outwardly extended to pass about the non-metallic supports between these points as at 30.

In Figure 9a where the laminated return circuits are spaced enough from the coil to permit the water-cooling tube to continue along the outside of the strips the tubing 28 is in continuous contact with the solid strips comprising the electrically conducting coil.

Connections with inlet and outlet tubing 19 and 20 are made through nipples 31 engaging with the tubing for example, at a point where it is not flattened.

In addition to the difference of Figures 9, 10 and 11 from 6, 7 and 8, in that magnetic return laminated material is shown at 27 instead of the coil supports, these latter figures differ also from Figures 6, 7 and 8 in that the flattened hollow conductors 28 are not continuous about the coil but are interrupted by the insertion of connecting tubing 18' to provide for transition about the laminated magnetic return circuit.

In both of the forms shown in Figures 6 to 11 the same hollow water-cooling conductor is connected to cool a number of conductors in parallel, making up a complete turn of the inductor and engaging the contour of these conductors at intervals or following the contour with such continuity about the 125

circumference as may be required to cool the inductor effectively.

In all of the forms the liquid conduit is on the outside where it is protected from flow of molten metal not only by the turns of the inductor itself but by any electrical insulation or other filling which may be desired, permitting complete sealing of the melt from the water-carrying tube by a wall formed by the current-carrying part of the inductor and the insulation within it and between its conductors.

The selection of the form of cooling and the number of places about the circumference of the coil at which the cooling is applied depend, of course, upon the needs of the individual installations. My illustrations for this reason have been suggested merely as ways in which my invention may be carried out so as to place the cooling tubing on the outside where leakage of water from it will least affect the charge and furnace and where the tubing is best protected from flow of metal from the charge. The cooling system is not confined so as possibly to result in a serious explosion if it be overheated.

For large furnaces of the high frequency induction type holding, for example, five tons of steel, it would be desirable to have the furnace coil made of a plurality of layers of edgewise wound copper strips or straps approximately as shown in Figures 8 and 11. Very thin insulating material, such as mica, should be used between the individual turns to prevent setting up of eddy currents and it is desirable to have the copper or other conductor as close as possible to the furnace charge. Not all of the conductors of a turn need be in thermal contact with the cooling element. In Figure 12 alternate layers of the strap conductors extend further away from the furnace charge than the layers of conductors between them, so that the cooling water is still further removed from the hot metal for the sake of safety. In such a construction good heat-conducting contact is desirable between the intervening strips and those engaging the tube.

The use of a water cooled tube continuously engaging the outer edge of the coil, as shown in Figure 9a, would be more effective and less likely to give trouble than the other forms.

In view of my invention and disclosure variations and modifications to meet individual whim or particular need will doubtless become evident to others skilled in the art, to obtain part or all of the benefits of my invention without copying the structure shown, and I, therefore, claim all such in so far as they fall within the reasonable spirit and scope of my invention.

Having thus described my invention, what I claim as new and desire to obtain by Letters Patent is:

1. In a cooling system for furnace coils, an inductor and water-cooled tabs at intervals on the outside of the inductor adapted to cool the inductor and protected from the furnace charge by the body of the inductor. 70

2. In an electric furnace an inductor coil of edge-wound material, tabs connected with the inductor at intervals and extending outwardly from the inductor and water-cooled connections with the tabs for cooling the 75 inductor through the tabs.

3. In an electric furnace, an inductor coil, water-cooled connections outside of the coil at intervals and tubing between the connections to supply the water cooling progressively about the inductor length.

4. In an electric furnace, a vertical inductor coil, magnetic material spaced at intervals about the inductor to form a magnetic return path, water-cooled tubing thermally connected with the inductor, to cool it at intervals between the magnetic circuit parts, and connections about the magnetic circuit to supply water to the tubing. 85

5. In an electric furnace, an inductor and water-cooled device for cooling the inductor, thermally connected with the inductor at intervals about the inductor length and separated from the inductor, and connections between the devices to supply water to them. 90 95

6. In an electric furnace, a solid metal primary winding, solid metal tabs connected to the primary at intervals along the length of the primary and water-cooled tubing in heat-transferring connection with the tabs.

DUDLEY WILLCOX.
